UNITED STATES PATENT OFFICE.

STEPHEN J. LEO, OF JERSEY CITY, NEW JERSEY.

CARTON FOR HOLDING VACUUM TUBES AND THE LIKE.

Application filed October 27, 1925. Serial No. 65,172.

This invention relates to cartons made from pasteboard or similar material, and adapted to be used commercially for holding vacuum tubes, electric light bulbs or the like, so as to protect the same from injury while being handled.

The general object of the invention is to provide a container which may be sealed, so that it is impossible to remove the tube therefrom, or to substitute a used tube, without breaking the seal or some other part of the carton, so that if the seal is unbroken, the customer may be sure that he is getting a new tube. The carton is so constructed, however, that the tube may be tested without removing the same from the carton.

The specific construction of the invention, and its advantages will be more fully explained in connection with the accompanying drawings, which illustrate one embodiment thereof.

In the drawings:

Figure 1 is a perspective view showing the container before the tube is placed therein.

Figure 2 is a central vertical section showing the tube in the container, and the latter sealed.

Figure 3 is a perspective view of the same with the cover removed.

Figure 4 is a horizontal section on the line 4—4 of Figure 2.

Figure 5 is a perspective view of the container after the tube is sealed therein.

Figure 6 is a perspective view of the outer casing before it is applied to the container.

Figure 7 is a perspective view of the inner box portion.

Figure 8 is a perspective view of the neck portion of the container.

Figure 9 is a perspective view of the corrugated paper lining.

The invention in its present embodiment is adapted to receive a vacuum tube 10 having a base 11 provided with terminals 12.

The carton comprises an inner rectangular box portion 13, open at the bottom, and having a top 14 with a central circular opening 15 through which the base 11 may protrude. This inner box portion is adapted to fit within

an outer rectangular casing 16, and is permanently secured thereto by wire stitches 17, or other suitable means. The casing 16 has a flap 18 at its lower end, which is initially left open, as shown in Figure 3, so that the tube may be inserted.

A rectangular neck portion 19 is adapted

to fit within the upper end of the inner box portion 13, and the bottom of this neck portion is provided with a central circular opening 20, slightly larger than the opening 15, and adapted to fit the fragile portion of the tube 10. In packing the tube in the carton, the bulb is surrounded with a protective covering 21 of corrugated paper, or the like, and the bottom of the carton is filled with suitable wadding 22.

After the tube has been packed within the carton, the flap 18 is closed and sealed by a suitable binder 23, and the tube can not then be removed from the carton without breaking the seal, or destroying some other part of the carton. The inner box portion 13 projects somewhat above the outer casing 16, as shown in Figures 1, 2 and 3, and is adapted to receive a cover 24. The base 11 of the tube projects above the inner box portion 13, but is sufficiently protected by the cover 24. When the latter is removed, however, the base portion 11 may be inserted in a suitable socket for testing the same without removing the tube from the carton.

The upper end 14 of the inner box portion is preferably provided with diagonal perforated lines 25, which may be easily broken when it is desired to remove the tube from the carton for use. As long as the lines 25 and the seal 23 remain intact, however, the purchaser may be assured that he is getting a new tube. The top 14 may, if desired, be inscribed with the notation that if the perforations are broken the guaranty is also broken.

While I have shown and described one specific form in which the invention may be embodied, it is apparent that various modifications may be made in the size, shape and proportion of the various parts thereof without any material departure from the essential features of the invention as claimed.

What is claimed is:

1. A carton for holding a vacuum tube or the like, comprising an outer casing, an inner box portion secured to the outer casing and projecting above the same and having a continuous integral top with an opening adapted to fit the base of the tube but not large enough to permit passage of the larger portion thereof, means for closing and sealing the lower end of said casing after the tube has been placed within the inner box portion with its base projecting through said opening, so that the tube cannot be removed

from the carton without breaking the seal or some other part of the carton, and a removable cover adapted to fit over the projecting portion of the inner box to protect 5 the base of the tube.

2. A carton for holding a vacuum tube or the like, comprising an outer casing, an inner box portion secured to the outer casing and having a continuous integral top with an 10 opening adapted to fit the base of the tube, a flap adapted to close the lower end of the inner box portion, and means for sealing the lower end of the casing to retain the flap after the tube has been placed within the 15 inner box portion with its base projecting through said opening, said top having rows of perforations extending from said opening toward the side edges, so that it may be easily ruptured to permit the removal of the 20 tube through the top.

3. A carton for holding a vacuum tube or the like, comprising an outer casing, an inner box portion secured to the outer casing and projecting above the same and having a top 25 with an opening adapted to fit the base of the tube but not large enough to permit passage of the larger portion thereof, a neck portion fitting within the inner box portion beneath said top and having an opening to 30 fit the smaller portion of the bulb, means for closing and sealing the lower end of said casing after the tube has been placed within the inner box portion with its base projecting through said opening, so that the 35 tube may not be removed from the carton without breaking the seal or some other part of the carton, and a removable cover adapted

to fit over the projecting portion of the inner box to protect the base of the tube.

4. A carton for holding a vacuum tube or the like, comprising an outer casing, an inner box portion secured to the outer casing and projecting above the same and having a top 40 with an opening adapted to fit the base of the tube, a neck portion fitting within the inner box portion beneath said top and having an opening to fit the smaller portion of the bulb, a flap adapted to close the lower end of the inner box portion, means for sealing the same after the tube has been placed 45 within the inner box portion with its base projecting through said opening, said top having rows of perforations extending from said opening toward the side edges, so that it may be easily ruptured to permit the 50 removal of the tube through the top, and packing adapted to surround the bulb between the flap and said neck portion and to hold the latter against said top.

5. A carton for vacuum tubes and the like 55 comprising, in combination, a sealed casing and a removable cover therefor, said casing having a perforation in its top through which the neck of the tube projects into the cover so that it may be tested without removal from the casing, and having provision 60 to be torn or ruptured so that the tube may be easily removed from the casing; the construction being such that a new tube may not be removed and an old one substituted 65 therefor without detection.

In testimony that I claim the foregoing as my own, I have hereto affixed my signature.

STEPHEN J. LEO.
